(57) **CLAIM**

The ornamental design for a battery for a wearable physiological monitor, as shown and described.

DESCRIPTION

FIG. 1 is a top perspective view of a design for a battery for a wearable physiological monitor showing our new design; FIG. 2 is a front view thereof; FIG. 3 is a rear view thereof; FIG. 4 is a left side view thereof; FIG. 5 is a right side view thereof; FIG. 6 is a top view thereof; FIG. 7 is a bottom view thereof; FIG. 8 is a top-front perspective view thereof, shown in an environment of use; FIG. 9 is a top-rear perspective view thereof, shown in an environment of use; FIG. 10 is a top-front perspective view thereof, shown in a second environment of use; FIG. 11 is a bottom-rear perspective view thereof, shown in a second environment of use; and, FIG. 12 is a top perspective view thereof, shown in a third environment of use.

The broken lines depict portions of the battery for a wearable physiological monitor and environmental structure which form no part of the claimed design.

1 Claim, 11 Drawing Sheets
